UNITED STATES PATENT OFFICE.

ELBERT B. RALEY, OF MART, TEXAS.

POWDER-DUSTING ATTACHMENT.

Application filed July 6, 1920. Serial No. 394,119.

To all whom it may concern:

Be it known that I, ELBERT B. RALEY, a citizen of the United States, residing at Mart, in the county of McLennan and State 5 of Texas, have invented certain new and useful Improvements in Powder-Dusting Attachments, of which the following is a specification.

My invention relates to a device, preferably embodied in an attachment, to be applied to or used in connection with a cultivator, or like wheeled agricultural implement, for applying an insecticide, preferably in a powdered form, to plants, such 15 as the cotton plant, for destroying boll weevils.

An important object of the invention is to provide an attachment of the above mentioned character, which may be applied to 20 the ordinary cultivator, without materially altering the construction thereof.

A further object of the invention is to provide a device of the above mentioned character, which is adapted to properly 25 spray a plurality of rows of plants, at the same time.

A further object of the invention is to provide means for properly agitating the 30 powdered insecticide, while in the hopper, and feeding the same in proper amounts, into the pressure chamber or casing.

Other objects and advantages of the invention will be apparent during the course 35 of the following description.

In the accompanying drawings forming a part of this specification, and in which like numerals are employed to designate like parts throughout the same,

Figure 1 is a plan view of a machine embodying my invention,

Figure 2 is a section taken on line 2—2 of Figure 1;

Figure 3 is a transverse section taken on line 3—3 of Figure 1;

Figure 4 is a vertical longitudinal section taken on line 4—4 of Figure 3;

Figure 5 is a horizontal section through the hopper, the agitator and associated elements being removed;

Figure 6 is a plan view of the rotatable disk-valve;

Figure 7 is a perspective view of the pressure chamber or receptacle;

Fig. 8 is a side elevation of a stop or bracket carried by one of the pivoted extension bars;

Fig. 9 is a rear end elevation of the apparatus, and,

Fig. 10 is a transverse section taken on line 10—10 of Figure 1.

In the drawings, wherein for the purpose of illustration is shown a preferred embodiment of my invention, the numeral 10 designates the cultivator frame, having connection with a tongue 11. This frame 65 extends rearwardly and is connected with the arched portion of an axle 12, upon which wheels 13 are rotatably mounted.

My apparatus or attachment embodies an attaching frame 14, including longitudinal bars 15, extending over the arched portion of the axle, and over the cultivator frame 10. The longitudinal bars 15 are connected at their forward ends with a transverse bar 16, arranged above and upon 75 the frame 10 and suitably secured thereto. The longitudinal bars 15 have intermediate portions 17, converging rearwardly, into portions 18, which are arranged in close relation and constitute the reduced end of the 80 attaching frame. An operator's seat 19 is carried by a support 20, which may be attached to a transverse bar 21, in turn attached to members 18.

The device further embodies a support 85 frame, including outer longitudinal bars 22, extending longitudinally of the machine below and connected with the arched portion of the axle 12 by U-bolts 22'. The forward ends of these bars are secured to 90 the forward transverse bar 16, while their rear ends have connection with a rear transverse bar 23, having extensions 24, pivoted thereto, at 25, and adapted to be swung to outer horizontal positions, and supported 95 by brackets 26.

Arranged within and between the converging portions 17 of the bars 16, are angle irons 27, secured thereto by bolts 28 or the like. The numeral 29 designates a vertical 100 preferably cylindrical hopper, having a bottom 30, which is bolted to the angle irons 27, as shown at 31. The top of the hopper may be reinforced by a ring 32, carrying bolts 33, having winged nuts 34, holding a 105 cover 35 normally upon the hopper, and allowing of its removal, when desired.

As more clearly shown in Figure 4, the stationary hopper bottom 30 has an outlet opening 36, leading into a vertical pipe 37, 110 as shown. An inlet opening 38, preferably arranged diametrically with relation to the

outlet opening 36, is formed in a stationary false bottom 39, also held in place by the bolts 31, and spaced from the bottom 30 the inlet opening 38 may be partly covered and 5 uncovered by means of a slide valve 38', as shown. The numeral 41 designates a rotatable disk-valve, operating between the bottom 30 and false bottom 39, and having preferably curved slots 42 formed therein, providing spaced fingers 43, preferably connected by a rim 44. The disk-valve has an 10 upwardly offset hub 45, receiving a boss 46 formed upon the bottom 30.

The disk-valve is rotated by a vertical 15 shaft 47, extending through an opening in the boss 46 and an opening in the hub 45. The shaft carries a transverse pin 48, fitting within openings or recesses 49 in the hub 45, whereby the disk-valve rotates with the vertical shaft. The upper end of the shaft 47 is screw-threaded, at 50, for engagement with a coupling 51, rigidly secured to an 20 agitator hub 52, carrying radially extending arms 53, having downwardly bent ends 25 54.

The means to drive the shaft 47 includes a bevel gear 54', suitably connected with its lower end, and engaging a bevel gear 55, rigidly secured to a transverse driving 30 shaft 56. This shaft is journaled in bearings 57, integral with the angle irons 27. One end of the shaft 56 is journaled in a bearing 58, carried by a diagonal brace 59, which may be clamped to the vertical portion 35 of the axle. A clutch element 60 is rigidly secured to one end of the shaft 56, and has ratchet teeth to engage with ratchet teeth formed upon a coacting clutch element 61, rotatable upon the shaft 56, and moved 40 inwardly by the spring 62. A sprocket wheel 63 is formed integral with the clutch element 61 and engages a sprocket chain 64 extending forwardly to engage a sprocket wheel 65, connected with one wheel 13, for 45 rotation therewith. The function of the clutch elements is to provide means whereby the disk-valve and agitator will be driven when the cultivator is traveling forwardly, but will not be operated when the machine 50 is being turned around or moved rearwardly.

The numeral 66 designates a rotary blower, embodying a casing arranged upon and supported by a transverse bar 67, bolted 55 to the bars 15. This blower casing is arranged in advance of the hopper 29, and the fan element of the blower is driven by a transverse shaft 68, having one end journaled 60 in the blower casing, and the other end in a bearing 69, carried by the bar 15. A sprocket wheel 70 is rigidly secured to the outer end of the shaft 68, and engages a sprocket chain 71 extending rearwardly to 65 engage a sprocket wheel 72, rigidly secured to the shaft 56. The blower casing has its

outlet end connected with a pipe or hose 73, see Figure 4, connected with a casing 74, having an opening 75 to receive the lower end of the pipe 37. The casing 74 is adapted to telescope within a pressure casing or 70 chamber 75, and may be clamped therein by a set screw 76 or the like. A plurality of 75 couplings 77 are secured to the forward end of the pressure casing 75, and have connection with hose 78, extending rearwardly to be supported upon the bar 23. The two outer hose 78 are extended outwardly, while the inner hose 78 extends rearwardly, and when three of the hose are employed, three rows of plants may be sprayed at the same 80 time.

The operation of the machine is as follows:

The cultivator is drawn forwardly over the rows of plants, and the disk-valve 41 is 85 rotated, with the agitator. The powdered material within the hopper 29, is stirred by the agitator, and falls into each slot 42 as it is brought in registration with the opening 38, the extent of this opening being regulated by slide valve 38'. The powdered material is carried around and dropped into and through the opening 36, and passes through pipe 37 into casing 74, and is blown by the compressed air from the blower through casing 75, and hose 78 to or upon the plants. By swinging the extensions 24 outwardly to 95 assume a horizontal position, Figs. 1 and 9, the hose 78 may have their outer ends suitably supported, and this will increase the 100 transverse range of the machine.

It is to be understood that the form of my invention herewith shown and described is to be taken as a preferred example of the 105 same, and that various changes in the shape, size, and arrangement of parts may be resorted to without departing from the spirit of my invention, or the scope of the subjoined claims.

Having thus described my invention, I 110 claim:—

1. In an attachment for a cultivator or the like including an arched axle, an inner longitudinally extending attaching frame disposed above and contacting with the arched portion of the axle, a blower arranged upon the forward side of the arched axle and connected with the attaching frame to be supported thereby, a hopper arranged upon the rear side of the arched axle and connected with the attaching frame to be supported thereby, a pressure chamber for receiving material from the hopper and connected with the blower to receive air under pressure therefrom, means to drive the blower, an outer supporting frame extending longitudinally beneath the arched portion of the axle and suspended therefrom, means connecting the forward end of the attaching frame with the forward end of the outer 120 125 130

supporting frame, a transverse supporting bar connected with the rear end of the outer supporting frame, and a plurality of conduits connected with the pressure receptacle and adapted to be supported by the supporting bar.

2. In an attachment for a cultivator or the like including an arched axle, an inner longitudinally extending attaching frame arranged above and resting upon the arched portion of the axle, a transverse bar connected with the forward end of the attaching frame, an outer supporting frame extending longitudinally beneath the arched portion of the axle and suspended therefrom and having its forward end connected with the forward transverse bar, a blower arranged upon the forward side of the arched portion of the frame and supported within the attaching frame, a hopper arranged upon the rear side of said arched portion and supported within the attaching frame, a pressure chamber connected with the hopper and connected with the blower, feeding

means to discharge material from the hopper into the pressure receptacle, means to drive the blower and feeding means, and a plurality of conduits connected with the pressure receptacle and extending rearwardly to be arranged upon the rear end of the outer supporting frame.

3. In an attachment for a cultivator or the like, a longitudinally extending frame secured thereto, a transverse bar connected with the rear end of the supporting frame, a pair of extension bars pivotally connected with the ends of the transverse bar to swing longitudinally of the transverse bar and transversely of the supporting frame, U-shaped stops carried by the extension bars and adapted to engage over the transverse bar, a plurality of conduits adapted to have their free ends supported by the transverse bar and bar extensions, and means to blow finely divided material through the conduits.

In testimony whereof I affix my signature.

ELBERT B. RALEY.
